Edward E. Kleinschmidt, Highland Park, Ill., assignor to Teletype Corporation, Chicago, Ill., a corporation of Delaware

Application December 28, 1935, Serial No. 56,496

23 Claims. (Cl. 178—36)

The present invention relates to printing telegraph apparatus employing pneumatically actuated mechanisms operated under the control of electrical signals.

5 An object of the present invention is to provide a fluid pressure actuated apparatus for recording electrically transmitted telegraph signals in which the phase relationship between the signal receiving mechanism and the fluid control mechanism may be varied, in which pressure resistance to the operation of control valves is minimized, and in which intermittent actuation of a distributor valve affords improved fluid channeling.

10 In the attainment of these and other objects there is contemplated in accordance with the present disclosure, novel mechanical embodiments featuring an arcuate disposition of typing elements having presented in close proximity thereto pneumatic actuating pistons. Fluid pressure obtained from a central distributing point is selectively conducted to piston chambers associated with each of the aforesaid pistons in accordance with the permuted disposition of 15 a set of selecting plates; the latter elements are provided with transverse connecting apertures so arranged that in accordance with the disposition of the several of said plates, each plate having two rest positions, there is obtained an individual transverse alignment of apertures through which there may be admitted a source 20 of operating fluid to motivate the particular selected one of several actuating pistons.

25 The aforesaid selector plates correspond in number to the number of signal impulses constituting the basic permutation code employed. In the example described hereinafter, a five impulse signal has been arbitrarily selected for the sake of illustration. The signal impulses may originate as electrical variations of minute duration grouped to comprise so-called permutation signals. The electrical potentials are designed to control the admission of fluid pressure through 30 slide valve means whence they are admitted successively to piston chambers associated with selector plate actuating pistons whose function consists of the shifting of the aforescribed selector plates to prepare the ultimate path through which the operating fluid is subsequently admitted.

35 In the performance of said distributor, certain principles of synchronism control, sometimes referred to as start-stop distribution, are employed for channeling fluid supply from a common source to each of a set of subordinate ar-

40 teries in much the same manner, figuratively speaking, that this principle has been heretofore known more exclusively in connection with electrical signal distribution. In this connection, improved methods and apparatus will be herein disclosed having particularly in mind the means and method of electrical distribution shown in 45 U. S. Patent No. 1,998,993.

46 A more comprehensive understanding of the present invention may be had by referring to the accompanying drawings and by reading the following detailed specification wherein like reference characters are employed to designate similar parts throughout, and in which

50 Fig. 1 is a plan view of a preferred embodiment of the present invention featuring a pneumatically actuated printer designed for use in continuous printing on a narrow strip of tape;

Fig. 2 is a detailed side elevation taken approximately on line 2—2 of Fig. 1 having portions broken away to reveal structural detail of the distributor;

Fig. 3 is a front elevation of the mechanism illustrated in Fig. 1;

Fig. 4 is an end elevation taken approximately on line 4—4 of Fig. 3;

Fig. 5 is a fragmental detail elevation of the distributor mechanism and selector housing taken approximately on line 5—5 of Fig. 3;

Fig. 6 is a detail sectional view with parts broken away taken approximately on line 6—6 of Fig. 3;

Fig. 7 is a fragmentary plan view of a printing mechanism base structure in which portions have been broken away to illustrate by way of example an arrangement of channels between the selector mechanism and the actuator pistons;

Fig. 8 is a transverse sectional view taken approximately on line 8—8 of Fig. 3;

Fig. 9 is a detail sectional view taken approximately on line 9—9 of Fig. 7;

Fig. 10 is a plan view of the mechanism viewed in Fig. 1 in which the distributor is partially in section and in which a major portion of the printing machine has been broken away to reveal the underlying selector housing;

Fig. 11 is a longitudinal section taken approximately on line 11—11 of Fig. 4;

Fig. 12 is a diagrammatic illustration of representative elements of the present invention and circuit indications arranged in a succession of operation;

Fig. 13 is an isometric exploded view of the

essential elements which comprise the distributor mechanism;

Fig. 14 is an isometric exploded view of the duct channeling system leading from the distributor featured in Fig. 13 to the selector pistons; and

Fig. 15 is a detailed perspective view of a cover plate used in the selector mechanism illustrating the distribution of its jets 51.

Referring now more particularly to the drawings, the reference character 11 denotes a base structure, the lowermost portion of which is rectangular, as may be noted from Figs. 1 and 7, but the upper portion of which is of arcuate configuration in the region indicated 12. Supported in a nearly semi-circular formation are a set of type bars 13 of conventional form and collectively pivoted on an arcuate pivot rod 14 which lies embedded within a groove 15 traversing through the arcuate portion 12 concentrically. Each type bar 13 is aligned within an individual slot 16 and the several slots radiate from a center common to the arcuate formation 12 and its several associated elements.

From Figs. 8, 9, and 10 it may be noted that the type bars 13 each carries a type slug 17 and at its lower end is provided with an integrally formed projection 18 whose lowermost edge surface has a cam curvature against which there normally rests the foremost portion or nose of its associated actuating piston 19. Each type bar 13 is provided with an actuating piston 19 which is supported in a vertical position within a cylindrical piston chamber 21, the lower extremity 35 of which extends through the rectangular portion of base 11 but the upper portion of which is longitudinally divided by its associated type bar slot 16. Each piston chamber 21 terminates with a pressure supply artery 22, concerning 40 which more will be explained later. The amount of actuating fluid requisite to the propulsion of a piston 19 is comparatively small as is also the distance of movement thereof. Hence it will be understood that the transverse type bar slots 45 16 reaching downwardly and across each of the chambers 21 are sufficiently distant from the extremity of movement of each piston to constitute no leakage factor as between its artery 22 and the surrounding atmosphere. The several type bars 13 are maintained in their upright position as viewed in Figs. 8 and 9 because of the tension of their return springs 23, one end of which is articulated to a small pin 24 carried by the individual type bar and the other end of 50 which is linked through an appropriate opening of which there are several radially disposed within an anchor band 25 circumscribed about the arcuate section 12. The poised radial alignment of type bars 13 is assured by the disposition of an arcuate bumper 26 formed of buffer material and supported coextensively by a framework 27 of curved metallic strips which in turn are supported upon a pair of standards 28, see Figs. 1 and 4, to which are connected the radiating ears 29.

Laminated arteries

To permit of the compact arrangement of the cylindrical piston chambers 21, they are alternately staggered and comprise two arcuate alignments, as may be noted best from Figs. 1 and 7. Contrasting with this alignment, the arrangement of apertures from whence originate each of the aforescribed arteries 22 is substantially rectangular, Figs. 10 and 15. Each

of the apertures which have been indicated 31 at their selector sources leads to one of the apertures 22 associated with an actuating piston chamber 21 or to one of several other pistons to be described later which performs an incidental function auxiliary to the primary purpose of printing. A system of channels connecting said apertures 31 with those indicated 22 is formed by the composite partitioning of a set of shims indicated 32, 33, 34, and 35 separated by intervening duct plates 36, 37, and 38. These elements are best illustrated in Fig. 7. From this illustration taken together with the representative cross-sections of Figs. 8, 9, and 11, it will be understood that each plate or shim is provided with openings in accordance with a plan of distribution affording a continuous path leading from each of the apertures 31 through certain one or ones of the plates and shims, thence horizontally across a particular one of the plates 36, 37, or 38 to a point in alignment with one of the apertures 22, whence the path continues transversely through the remaining plates and shims, to one of the apertures 22.

Selector

The selector device is comprised of a set of contiguous plates, five in number, and of generally similar contour. The top selector plate 39 which aligns with each of two portions of the apertures 31 is provided with a predetermined arrangement of perforations and is capable of two positions during each of which the perforations of plate 39 are brought into registration with corresponding ones of the apertures 31. The next adjoining plate 41 is provided with apertures multiplied with respect to the apertures of plate 39 so that during each of its positions, a half portion only of the perforations of plate 39 are rendered communicative with the perforations of plate 41. Correspondingly, plate 42 is provided with a distribution of perforations arranged to align with half of the perforations of plate 41 during one of its positions and others of said perforations during its alternative position. In turn, each of the remaining plates 43 and 44 subserves to continue the perforation alignment of a portion of the perforations of its preceding plate so that in all, each plate of the group 39 to 44 functions to channel the path of a particular alignment of perforations into one of two alternative paths. Thus by reason of there being five selector plates 39—44, there is obtained a total number of selectable channels equivalent to the number 25 or 32.

Fluid pressure supply received through the intake jet 45, Fig. 11, passes through the aperture of elbow 46 until it is confronted by the barrel 47 of valve 48. In response to a control condition to be described later, a supervisory supply of fluid under pressure is received through conduit 49 and permitted to enter the chamber at the left of valve 48, urging the latter rightwardly against the tendencies of its spring 51. When this occurs, the passageway originating with the pressure supply source 45 is continued through the intervening space 52 of slide valve 48 to the duct 53, thence rightwardly to the central aperture 54. From this point the fluid pressure is admitted through the vertical vent 55 to a distributing chamber 56 with which there communicate a plurality of jets 57.

The chamber 56 is formed within an internal floating housing comprised of a bottom plate 58 and a cupped cover plate 59. This housing nor-

5 mally rests upon an elastic diaphragm 61. When fluid pressure is first admitted to the central aperture 54, its instant response is to dilate the space beneath the diaphragm 61, urging the floating housing 58—59 upwardly in opposition to the return springs 60, Fig. 8, and against the selector plates 39—44. This compression seals the several plates as between each other and also as between plate 44 and its subjacent jets 51. There-
10 after and following almost instantaneously the fluid pressure surges through the vent 55 into the distributing chamber 56 and continues on through one of the jets 51 and in accordance with the dis-
position of the several plates 39—44 seeks out a
15 course which terminates in a piston chamber 21 beneath one of the pistons 19 relating to a print-
ing function or one of the other pistons relating to a collateral function:

10 The aforescribed pressure introduction and its control is a cyclic occurrence following which the slide valve 48 is returned to its normal position as viewed in Fig. 11. The pressure which had been built up in the distributing chamber 56 is then permitted to be dissipated back through vent 55, central aperture 54, duct 53, to the intervening opening 52, thence out through the bleeder hole 62.

Distributor

30 The foregoing description relates to the mechanics of the selector apparatus but the timing of operation and the intercontrol of the various selecting and executing functions are supervised by a pneumatic valve mechanism generally referred to herein as the distributor. This device comprises a driving shaft 63 which is continuously rotated by an electromotor (not shown) through a driving gear train 64. The rotary movement is communicated through a friction assembly 65 to a driving disc 66 notched in its periphery to receive a horizontally bent section 67 of a driven arm 68 which is secured to the driven portion of the distributor shaft 69.

45 Shaft 69 is withheld in a normal or zero position which is determined by the angular arrangement at which an arm 71 carried by shaft 69, see Figs. 4 and 13, encounters the foremost end of a stop arm 72 pivoted at 73 and urged by a spring 74 in a direction away from the observer as viewed in Figs. 2 and 4 and rightwardly as viewed in Fig. 1. Opposing the action of spring 74 is a piston 75 which, during the start interval of the operative cycle, receives in its piston chamber sufficient fluid under pressure to overcome 50 the tendency of spring 74 and to move stop arm 72 from its effective position; that is, from the position whereat the foremost portion of arm 72 lies in the path of revolving arm 71 of shaft 69. During the major portion of a cycle, the chamber of piston 75 is without pressure, permitting arm 72 to continue in its effective position.

55 Upon the reception of a start impulse, a surge of fluid is communicated to the chamber of piston 75, thrusting the latter outwardly, as viewed in Fig. 11, and dislodging arm 72. This frees the revolving arm 71 and permits shaft 69 to enter upon a cycle of rotation carrying with it its several appurtenances which will be described later. While this arrangement serves to time the cyclic 60 rotation of shaft 69, bringing the latter to rest at the conclusion of each rotation, it is feasible that under certain conditions of operation where the electric control signals are permitted to succeed each other rapidly, that synchronism of shaft 69 may be maintained while permitting

an almost continuous rotation and without an appreciable stop during the zero position. This phase of operation deals of course with matters of adjustment and timing, the theoretical mode of operation being one of cyclic arrest and 5 restarting.

Shaft 69 extends rightwardly as viewed in Figs. 11 and 13 and is journaled at 76 in a rear plate 77 of the distributor and at 78 in a foreplate 79 thereof. Intermediate plates 77 and 79 there 10 is secured to shaft 69 a collar 81 with which there 15 is integrally formed a pair of cams 82 and 83, see especially Figs. 5, 6, and 13. Each cam 82 and 83 controls the actuation of a slide valve 84 and 20 85 and through these, shaft 69 during its rotation 25 and in the course of a single cycle thereof, effects a distribution of operating and control fluid from a source of supply indicated 86 to several subordinated channels as will be described.

The forward wall or foreplate 79 has within it 20 a vertical aperture 87 from which there branch two outlets, a lower one of which is indicated 88 and an upper one 89. The opening 89 comprises a narrow horizontal slit. Between the foreplate 79 and an adjacent block 91 there is interposed 25 a spacer plate 92, see Fig. 13. The latter is slotted as at 93 so as to afford a groove between the foreplate 79 and the block 91 within which there is received a blade or selector lever 94 pivoted at 95 on a pin carried by an extending ear 96 integrally formed with block 91. One end 97 of selector lever 94 is rounded and thereat by contactual engagement with an armature 98 of electromagnet 99 receives a shift movement counter-clockwise, as viewed in Figs. 2 and 13, during the 30 energization of magnet 99 and a return movement under impetus of spring 101 during other times manifesting by its position the nature of the impressed current impulses which are received over an incoming line and to which the 35 magnet 99 is electrically connected.

The opposite end of lever 94 is apertured as at 102 and in its two extremities of motion the aperture 102 of lever 94 comes into registration with one or another of a pair of slot openings 103 and 104 which extend transversely through block 91 and which incidentally are enlarged slightly as they approach the opposite face of block 91, as may be noted from Figs. 11 and 13. The horizontal slot 89 is located midway between the 50 apertures 103 and 104 of block 91 and the width of aperture 102 of lever 94 is just sufficient to align with slot 89 and either one or the other of apertures 103 and 104 depending, of course, upon the alternative conditions of selector lever 55 94. In the illustration of Fig. 13, this lever is shown in its clockwise extremity whereat it would connect slot 89 with aperture 104, aperture 103 being non-communicative or, more accurately, in communication with atmosphere. The alternative condition would find the relationship of slots 103 and 104 transposed.

Beyond the block 91 there are presented a pair of parallel spacer plates 105 and 106 between which there is afforded a sufficient clearance to 65 receive snugly the slide valve 84. Through the central portion of valve 84 are found four openings, the upper one is circular and is indicated 107; the next three are rectangular and are indicated 108, 109, and 111. Valve opening 108 is 70 presented in approximate alignment with the transverse openings 103 and 104 of block 91. With the slide valve 84 in its upper position, opening 108 is exclusively in registration with the enlarged portion of opening 103, but with 75

the valve 84 in its downward position, said opening 108 is in exclusive registration with the enlarged portion of opening 104.

Referring now again to the foreplate 79, attention is directed to the outlet 88. In registration with this outlet there may be found an opening 112 in spacer plate 92, an opening 113 in block 91, while in slide valve 84 the pair of openings 109 and 111 are arranged alternatively to be brought into registration with the continuation of said duct openings.

Beyond valve 84 is a distributor block indicated 114 which is provided with a series of centrally disposed slots parallelly arranged in a vertical alignment. The lowermost slots indicated 115 and 116 extend inwardly part way and thence continue for another distance rightwardly as viewed in Fig. 13 and at their remote interior section they are joined by a transverse opening 117. A conduit 49 aforesaid in connection with the slide valve 48 extends upwardly and inwardly into block 114 and connects with the interior portions of ducts 115 and 116, preferably in the approximate region 25 of artery 117.

Another pair of ducts indicated 118 and 119 also extend inwardly and rightwardly within block 114 and their innermost chambers are mutually connected by a pair of traversing arteries 30 indicated 121. A duct 120 extending perpendicularly from one of the ducts 121 continues out of block 114 through an opening 130 in one of a pair of spacer plates 140 and thence through a transverse channel 150 in plate 77. Beyond this 35 the channel continues through other portions of the distributor mechanism which will be discussed subsequently. Another slot indicated 122 and located above slot 118 extends transversely through block 114 where on the opposite face it 40 is enlarged as indicated at 123 to embrace a greater surface area in its engagement with slide valve 85. Above slot 122 there is found an elongated cavity 124, and leading therefrom are the interior ducts 125, 126, and the emergent duct 45 127. The aforesaid valve opening 107 may be made to align with duct 127 and to continue thereby the channel back through orifice 128 of block 91, hole 129 of spacer plate 92, thence through the traversing artery 131, whence the 50 channel is projected downwardly and sidewardly by the accommodations afforded by a furrow 132 in the forward surface of foreplate 79. Furrow 132 extends radially over a substantial area of the face of plate 79 so as to communicate with the chamber of piston 75 in whatever position 55 may be assumed by the latter, since the plate 133 in which the piston chamber of piston 75 is located is movable radially about shaft 69 to afford orientation in obtaining an adjustment 60 for the stop or zero position of shaft 69.

Referring again to distributor block 114, it will be noted that the enlarged cavity 123 of transverse slot 122 aligns opposite a cooperating flared opening 134 which tapers inwardly until it 65 becomes a comparatively narrow slit at the opposite face of slide valve 85 as indicated 135. It may be observed that the flared opening 134 communicates with the cavity 123 at all times but that the slit 135 comes into registration successively with a series of five parallelly aligned slits 136 to 141. Thus there may be traced a 70 line of communication for conducting fluid surges from the inlet 86 through outlet 89, thence over two courses selectively determined by the pneumatic selector lever 94. For purposes of dis-

tributing the signal impulses, one course continues through opening 104, opening 108 of slide valve 84, slot 122, and cavity 123, whence communication is afforded through the flared opening 134, narrow slit 135, and any one of the five 5 distributive slits 136 to 141. A secondary channelling in this course is controlled by slide valve 84 which during its up position, instead of aligning opening 108 with slot 122, brings it into registration with cavity 124 and opening 103, preparing the course which conducts the start impulse fluid surge to the piston 75. This course may be traced through opening 108 (when the slide valve 84 is in its upper position), cavity 124, ducts 125, 126, and 127, thence back through 15 opening 107, orifice 128, hole 129 to the traversing artery 131, thence out through furrow 132 to the piston chamber of piston 75. The last described course is prepared for the duration of a short interval once during each cycle when it 20 is desired to withdraw blocking arm 72 and to thereby effect synchronization. Thus it will be understood that only during this interval will slide valve 84 be found in its upper extremity and that during the major portion of the cycle, valve 25 84 may be found in its downward position as will be evident from the contour of cam 82, see Fig. 6. While shuttle valve 84 serves to control the introduction of operating fluid to piston 75, incidentally it also functions at a later interval 30 in its cycle to introduce operating fluid for the reproduction of line surges in accordance with the signal elements of each signal. Cam 82 during the effective interval of its long apex de-presses shuttle valve 84 until a continuous alignment is effected between opening 104, 108, and slot 122. This introduces fluid under pressure into the cavity 123 whence it remains communicative with the flared opening 134 during the 35 entire transit of shuttle valve 85 which includes 40 the time at which it communicates with each of the slits 136, 137, 138, 139, and 141. As may be understood from observing the contour of valve cam 83, see Figs. 5 and 13, shuttle valve 85 undergoes a series of short successive downward 45 movements coming to rest momentarily as the vent 135 is brought into registration with each of the afore-mentioned slits 136-141. By studying cams 82 and 83 together, it will be observed that the progressively involute surfaces 50 of cam 83 coincide radially with the apex of cam 82. Thus during the distributive portion of the cycle when shuttle valve 85 is active and is descending by successive steps, cam 82 maintains shuttle valve 84 depressed, keeping opening 108 of shuttle valve 84 in alignment with the openings 104 and 122. During this interval as the electrical potentials are impressed upon magnet 99, its armature 98 correspondingly shifts the selector lever 94, causing the opening 102 55 thereof to be alternately presented and withdrawn from registration with opening 104. During the interval in which opening 102 is moved upwardly out of registration with opening 104 it is, of course, brought into registration with 60 opening 103 which, as has been noted before, communicates with a series of openings that eventually lead back to the piston chamber of start piston 75. When this occurs during the distributive portion of a cycle, however, opening 65 108 is not in alignment with cavity 124 by reason of which the path is interrupted at shuttle valve 84. However, this is not an essential precaution for the reason that any energization of piston 75 during movements of the cycle other 70 75

than the start interval are at most ineffectual and do in no wise interfere with the rotation of shaft 69.

Duct 113 terminates at the hinder face, Fig. 13, of block 91 with a cupped recess 110, the diameter of which is great enough to overlap both rectangular openings 109 and 111 of slideable shuttle valve 84. Through opening 109 pressure is communicated to slot 113, ducts 121 and 120, hole 130 and canal 160 to a series of branch conduits leading to the chambers of the selector operating pistons to be described later. Through rectangular opening 111 fluid flowing through cupped recess 110 continues along slot 115, duct 117, out over conduit 49 to the piston chamber of cylindrical slide valve 48. This causes the latter to be shifted rightwardly, as viewed in Fig. 11, and to establish accordingly the aforescribed path for admitting the selector actuating fluid originating at intake 45.

As may be readily noted, slots 118 and 119 communicate with a common duct or channel of communication 120 and also slots 115 and 116 with a common channel of communication 49. The purpose of providing pairs of slots is to establish alternative paths, one of which is effective during each of the shift positions of shuttle valve 84 so that pressure previously built up and accumulated in their respective operating chambers may, during the alternative position of shuttle valve 84, be relieved through bleeder grooves such as those indicated 142 and 156 in block 91.

A pair of bails 143 and 144, Fig. 4, pivoted upon shoulder screws 145 and 146 are urged by springs 147, the former in a counterclockwise direction and the latter in a clockwise direction. In this way their sidewardly extending lugs 148 and 149 serve to maintain the shuttle valves 84 and 85 firmly against their respective cams 82 and 83.

There have been described the various pneumatic courses originating with current supply source 86 through blocks 79, 91, 114, and 77 as controlled by the moving elements 94, 84, and 85. The primary object obtained is the introduction of permutative current surges into the slits 136, 137, 138, 139, and 141 whence they emerge through individual enlarged canals 151, 152, 153, 154, and 155.

Calling particular attention to the illustration in Figs. 5, 11, and 14, it will be noted that immediately behind the distributor mechanism just described there is located a set of five pistons 157. Each piston 157 is capable of assuming two positions, one such as that illustrated in Figs. 11 and 14 before actuating current has been introduced into the piston chamber and another such as that indicated in dotted lines in Fig. 14. The current surges communicated through the aforescribed slits 136-141 find their way each to a corresponding one of the piston chambers of pistons 157. The channeling of these fluid surges is executed in the following manner. Emerging from the five enlarged canals 151-155, the paths continue through a shim 158 where canal 151 aligns with an opening 159, canal 152 with an opening 161, canal 153 with an opening 162, canal 154 with an opening 163, canal 155 with an opening 164, and the special duct 150 with an opening 165. Sandwiched between shim 158 and a succeeding shim 166 there is disposed a plate 167 in which are provided a series of divergent canals. One indicated 168 communicates with opening 159, 169 communicates with opening 161, 171 communicates with opening 162,

172 communicates with opening 163, 173 communicates with opening 164, and canal 174 communicates with opening 165. The destination of each of the canals having an origin in alignment with the afore-enumerated openings 159-165 corresponds to the openings indicated 175 to 181 of shim 166. A set of parallel ducts 182 continue the path in registration with the openings 175 to 179 but opening 181 aligns with an inlet duct 183 which communicates with an interior artery 184. A set of five jets 185 branching out of the interior artery 184 continue sidewardly and terminate with abbreviated projections 186. In alignment with the jets 185 and their projections 186 are a corresponding set of five openings 187 formed in a spacer plate 188. The openings 187 resemble key holes in the manner that they are associated with laterally extending notches 189, the extremities of which are adapted to register opposite the sets of parallel ducts 182 aforementioned.

Beyond the plate 188 there is found a piston block 191 which serves as a housing for the several selector pistons 157. The rearmost ends of the pistons 157 are provided with reduced portions or projections as indicated at 192, which during the retracted condition of their associated pistons 157 are disposed opposite the alignment of openings 187 and jets 185, serving in this manner to seal the jets 185. The actuating impulses which, as stated before, are distributed through the slits 136-141, travel through the openings 159-164 in shim 158, the canals of plate 167, the openings 175-179 of shim 166, the ducts 182 of block 180, the laterally extending notches 189 of plate 188, thence to the space afforded within the openings 187 surrounding the projections of the rearmost ends 192 of pistons 157. Pressure, introduced through any of the individual paths aforescribed collectively, will act against the cross-sectional area of a piston 157 exclusive of the reduced portions indicated 192. This will serve to move the pistons 157 a slight distance, following which their associated jets 185 will be opened, admitting additional pressure therethrough.

The latter force will be referred to for the sake of convenience as piston operating pressure, and is traceable from outlet 88, opening 112, duct 113, opening 109, duct 119, arteries 121, duct 120, thence through openings 130, 150, 165, 174, opening 181, duct 183 to the interior artery 184. The effect of supplying an initiating impulse and thereafter supplementing it with a general supply pressure permits of a practice wherein the pistons 157 may be dislodged by comparatively momentary pulses of fluid pressure, the operating pressure being supplied through the jets 185. As a result of this improved method of operation, it is found that the distributing element, in the instant case shuttle valve 85, is capable of operating at appreciably greater speeds. Otherwise, or where the distributed pulsations might be expected to execute the entire movement of the selector setting pistons 157, the time interval of distribution would require considerably more time than is necessary in the instant case.

At the conclusion of each selective cycle there occurs a short interval during which shuttle valve 84 is withdrawn from registration with recess 110 of duct 113 and moved upwardly so as to come into registration with the bleeder groove 156. When this happens, pistons 157 are permitted by independent spring pressure, to be restored to their normal position, the displaced

fluid percolating back through its respective channel, including one of the jets 185, artery 184, duct 183, opening 181, canal 174, openings 165, 150, and 130, duct 129, artery 121, duct 118, opening 109, and bleeder groove 156.

The several elements illustrated in Figs. 13 and 14 are preferably assembled and braced together by transversely extending securing means such as bolts, etc., the illustration of which has been omitted from these figures in order to avoid the unnecessary confounding of the views.

The five selector pistons 157 correspond to the five elements of a conventional five unit permutation code, each piston taking its operated or unoperated position in accordance with the marking or spacing attribute relating to a given signal. The positions of the pistons 157 are immediately communicated to five transfer levers indicated 193-197, see especially Figs. 4, 5, and 10. The opposite ends of levers 193-197 engage the set of selector plates 39-44, and each lever is urged counterclockwise by an individually associated spring 198, while the several plates 39-44 are normally urged in their rightward direction as viewed in Fig. 10 by individually associated springs 199 connected to integrally formed extending lugs associated with the selector plates. The tension of springs 199 is preferably regulated by adjustment screws 201 so as to be strong enough to return promptly the plates 39-44 after each setting while yet feeble enough to be overcome during the actuation of pistons 157.

It will be recalled that following each setting of the several selector plates, shuttle valve 84 operates to admit a surge of selecting fluid through conduit 49 and that when this fluid reaches the small central chamber 54, it tends first to inflate the space beneath the elastic diaphragm 61, causing the plates 58 and 59 to be pressed against the selector plates 39-44 and in this way to bind them momentarily in their set positions. Concurrently, the fluid pressure which is found within the enclosure 56 seeks out one of the apertures 57 which happens to be opposite a selected alignment of openings through the several plates 39-44, depending of course upon the particular disposition of said plates. The particular passageway thus selected continues through one of the apertures 31 and is conducted through grooves in one of the plates 36-38 or arteries 22 until it is ultimately led into the piston chamber 21 of a function actuating piston 19. The pressure accumulating in this chamber sends the piston 19 upwardly against the type bar lug 18, causing the bar 13 to be pivoted about shaft 14 and to swing its type slug 17 sharply against the printing ribbon 202 in the position in which it traverses the printing area behind the guide plate 203.

60 Case shift

The present embodiment contemplates a printing mechanism employing plural case print operations. The type slugs 17 each carry a pair of printing characters, one relating to each of the cases. The shifting between one and the other of the cases is determined by the longitudinal shifting of a printing platen 204. As best revealed in Fig. 8, the platen 204 is mounted upon a hub 205 which in turn is secured to and rotatable with a sleeve assembly 206. The latter is freely rotatable upon the stub shaft 207 and is capable of longitudinal movement thereupon throughout a distance determined on the one hand by its abutment with washer 208 and on

the other hand by the engagement of ratchet wheel 209 with the foremost portion of the frame structure 18.

The shifting of sleeve assembly 206 is executed under the primary control of a pair of pistons 222 and 223, the location of which will be easily understood by observing Figs. 1 and 3. Intermediate the piston chambers of pistons 222 and 223 and pivoted at 224 thereat is a shift lever 225. At one end of this lever a short portion 10 has been bent down and bifurcated as at 227, see also Fig. 8. The tines of the bifurcated portion straddle an annular rib 228 integrally formed with sleeve 206. Each of the alternative positions of lever 225 is detented by the engagement of a 15 tooth 229 integrally formed with detent spring 231, with notches 232 and 233 formed in the left end of lever 225, Fig. 1.

A pair of arteries indicated 234 and 235 in this figure supply the actuating fluid for propelling 20 pistons 222 and 223, the operation of one of which mechanically restores its companion piston to unactuated or normal position. Each artery 234 and 235 continues through a selective passageway traceable through the selector plates 39-44 aforementioned, and in response to delegated signals a shift operation may be thus executed. In order to permit the exhausting of certain piston chambers, as in the instant case the chambers of pistons 222 and 223, minute bleeder apertures may 30 be provided whose capacity is small enough to cause no interference with the actuating fluid surges but is of sufficient proportions to thereafter permit the depletion of the fluid pressure following the actuation of its associated piston. 35

In addition to serving as a medium for case shifting, platen roller 204 also provides the means for advancing the printing tape cyclically. This is obtained by rotating the platen intermittently. Figs. 3 and 9 illustrate the construction and location of a mechanism for actuating ratchet wheel 209 and through it the platen assembly. This comprises a piston 211 operating in chamber 212 and supplied with actuating fluid through an artery indicated 213. In the region marked 45 214 in Fig. 9, the continuation of this artery through the selector plates 39-44 differs in one respect from the remaining passageways relating to other of the arteries indicated 31, in that the openings of the selector plates in the special case 50 are designed so as to remain in alignment during all conditions of the selector plate; thus fluid pressure is admitted over the course indicated 214-213 concurrently with the establishment of each and every passageway. Thus it follows 55 that piston 211 is actuated contemporaneously with any of the other pistons 19.

In moving upwardly, the rim of piston 211 engages a jutting pin 215 carried by the pivot screw 216 whereat tape advancing pawl 217 is articulated to the supporting arms 218. The actuating movement of piston 211 in this way stimulates the return stroke of pawl 217. The feed stroke, however, is urged by a spring 219 which connects with a downwardly extending arm 221 65 that forms part of an assembly with supporting arms 218. As the pawl 217 is actuated by piston 211 pursuant to its return stroke, a detent pawl 236 pivoted at 237 and urged by a spring 238 engages the teeth of ratchet wheel 209, latching 70 it against any tendency to return in a direction opposite its tape advancing direction of rotation.

The printing ribbon is preferably carried upon a pair of spools 239 pivotally supported upon posts 240. One of the spools is a supply spool and the 75

other a winding spool so as to permit the ribbon to advance new areas during regular printing operations. Conventional types of spool actuating mechanism may be employed for this purpose, a specific embodiment of which is not deemed essential in understanding the principles of the present disclosure.

Referring now more particularly to Figs. 1, 3, and 4, attention is directed to the tension roller assembly comprising a pair of friction rollers 241 and 242 pivotally carried by a lever arm 243 which is pivoted upon a fixed pivot screw 244. The latter is anchored to a sidewardly and upwardly extending projection 245 integrally formed with guide plate 203. A channel member 246 serves to guide the incoming tape preparatory to its approach to the first tension roller 242, and it is secured to the lever arm 243 so as to operate together therewith. The assembly including channel member 246, arm 243, and roller 241 is maintained in its counterclockwise extremity as viewed in Fig. 3, by the influence of a tension spring 247 articulated to the lever 226, Fig. 7, and to a binding post 248 carried by arm 243, Fig. 1.

Operation

In the illustration of Fig. 12, a rudimentary and simplified diagram has been featured employing several constructional representations and conventions in order to facilitate a comprehensive understanding of the present invention within a single diagrammatic concept. A sufficient resemblance has been invoked with regard to some exemplary details in order to suggest in each case the corresponding structure which is more accurately illustrated in the remaining views.

The reference character 99 indicates an electromagnetic selector element which is located in a signalling line and which responds to the current pulsations by the attraction and release of its armature 98. This movement on the part of the armature 98 is communicated to selector lever 94, which by spring 101 is made to follow faithfully the movements of armature 98. During its alternative positions, the aperture 102 comes into alignment with one or the other of the openings 103 or 104 and accordingly continues a path leading from outlet 89. Fluid conductor 249 symbolically represents the path originating in the opening 103 and thereafter a secondary selection is effected by shuttle valve 84. At the proper time interval in each cycle, this path is continued through ducts 125, 126, and 127, thence out through opening 107, following which the path is represented by fluid conductor 251 which leads to the piston chamber of start-stop piston 75. Thus it will be seen that when shuttle valve 84 is in its upward position as determined by cam 82 and when shaft 69 is at rest, the admission of a fluid impulse through opening 103 acting through piston 75 supplies an initiating stimulus by withdrawing stop arm 72 from the path of revolving arm 71.

Fluid surges admissible through opening 104 travel through a conduit symbolically represented and indicated 252, where under the influence of shuttle valve 84 and opening 109 thereof they are admitted over symbolic course 253 to the flared opening 134 where, by the movement of shuttle valve 85, the pulses are successively distributed to the slits 136-139 and 141. Meanwhile, the movement of shuttle valve 85 also regulates the admission of holding fluid pressure originating at source 86 and controlled through cavity 111

and continued over symbolic courses 254 or 255. The former course, indicated 254, ultimately leads to the artery 184 from which a set of five jets 185 leads to the chambers of pistons 157. Because the jets 185 are normally sealed, however, the effectiveness of this supply is contingent upon the actuation of one or more of the pistons 157 in response to an initiating fluid surge receivable through the selector openings 136-139 and 141. After having become actuated, however, the pistons 157 are moved their entire distance of travel by the augmenting supply of power fluid receivable over course 254 and thereafter by mechanical linkage diagrammatically indicated 256 the movements of pistons 157 are imparted to their associated selector plates 39-44.

Thereafter, fluid is admitted over course 255, which functions first to force bottom plate 58 and cover plate 59 upwardly to clamp together the selector plates 39-44 and thereafter to seek out a prepared channel including one of the apertures 31, arteries 22, and ultimately the selected piston chamber of one of the pistons 19, 211, or 222.

While the present invention has been explained and described with contemplation of a particular embodiment, it is noteworthy that numerous modifications and variations may be instituted without departing from the spirit or scope thereof. Accordingly, it is not intended to be limited by the specific language of the foregoing specification nor by the particular illustrations in the accompanying drawings but to be permitted instead a latitude of interpretation as indicated by the hereinafter appended claims.

What is claimed is:

1. In a device for channeling pneumatic current, a main body having a groove and affording thereat opposite parallel surfaces, a reciprocable valve supported in said groove having wiping engagement with each of said surfaces and comprising a flat body having a central opening with adjoining solid portions, said main body having conduit channels traversing said groove in registration with said flat body, and electromagnetic means for moving said flat body laterally accordingly to present or withdraw its said opening with respect to said conduit channels.

2. In a telegraph communication system, a device for converting telegraphic signals into corresponding fluid surges including a main body having a groove and conduit channels traversing said groove, a blade element laterally movable within said groove and in wiping engagement with the sides thereof and having a central opening presentable into registration with said channels, and electro-responsive means for moving said blade element.

3. In a telegraph printing apparatus, a plurality of type carriers having multiple type characters; a platen shiftable into alternative alignment corresponding with each of said characters, and electro-pneumatic means for shifting said platen comprising a lever articulated to said platen, a pair of pistons supported in piston chambers and disposed in opposition to each other for shifting said lever, conduit means connecting a source of fluid supply with each of said piston chambers, and routing means for alternatively associating said conduits with said source of fluid supply.

4. The combination set forth in claim 3 in which said routing means includes a set of contiguously disposed selector plates having permutably arranged openings transversely thereof and

electro-pneumatic actuators for variously positioning said plates to afford an individual alignment of said transverse openings.

5. A device for routing fluids comprising a main body having a groove which affords opposite parallel surfaces, said body having a plurality of branch channels terminating at one of said surfaces with individual spaced terminal openings, said body having an artery terminating at the other of said surfaces in a proximity equidistant from said spaced openings, a valve plate movable within said groove and having an opening co-extensive with said artery terminal and each of said spaced openings individually, and electromagnetic means for moving said plate to associate with said artery each of said spaced openings selectively.

6. The combination set forth in claim 5 in which said electromagnetic means comprises a magnet winding electrically connected with a signal communication line, and an armature influenced by said winding for moving said plate accordingly.

7. In a pneumatic distributing mechanism, a body having two parallel channels terminating at a common surface and adjacent each other and having a supply source channel opening in a surface opposite said parallel channels, and a lever for controlling the connection between said supply source channel and said pair of parallel channels including a valve portion having an opening therethrough of size to embrace said supply channel and either of said pair of parallel channels to the exclusion of the other of said pair of parallel channels, said lever having wiping engagement with said common surface and said opposite surface.

8. The combination set forth in claim 7 including an electromagnet having an armature for controlling the actuation of said lever, and spring means for urging the continuous association of said lever and said armature.

9. In a device for selectively controlling the passage of fluid from a supply source to each of a plurality of channels, a body affording a surface at which terminate the ingress openings of a plurality of branch channels in spaced relation each to each, said body affording an arterial channel for said supply source opposite said branch channels, a controlling lever presented intermediate the terminals of said arterial and said branch channels in wiping engagement with each of the adjoining surfaces thereof having a plurality of selective conditions, said lever comprising a flat portion having an opening transversely thereof and movable to associate said arterial channel with each of said branch channels individually during each of its said selectable positions.

10. In a signal distributing mechanism, a rotatable shaft, a supporting plate, stop means for arresting said shaft carried by said supporting plate, a pneumatic actuator for releasing said stop means, and means for changing the angular position in which said stop means effects the arresting of said shaft comprising a member cooperating with said plate having a channel through which fluid is conducted to said pneumatic actuator, and an arcuate groove terminating said channel and communicating with the chamber of said actuator angularly through its distance of movement.

11. A device for controlling and distributing fluid surges comprising a control shaft, a pair of members having transverse arteries, a shuttle

valve intermediate said members and longitudinally slidable therebetween having transverse openings movable into and withdrawable from said transverse openings of said members, a control cam carried by said shaft, and spring means for urging said valve against the periphery of said cam.

12. A mechanism for distributing fluid surges comprising a rotatable shaft, a valve of flat material movable longitudinally, a closely defining housing surrounding said valve having an opening transversely of said valve flared at one side and tapering to a reduced slit at the other side thereof, a portion on one side of said valve having a supply duct communicable with said flared opening, a portion on the opposite side of said valve having a plurality of slits parallelly arranged in an alignment corresponding to the path of said reduced slit in said valve, and an actuator for bringing said reduced slit of said valve into registration with said plurality of slits of said portion comprising a cam carried by said shaft having short dwells distributed in equally spaced radial distances on the periphery of said cam.

13. A mechanism for controlling the passage of fluid through a plurality of parallel channels comprising a pair of terminal blocks having transversely thereof a plurality of channel ways, a shuttle valve traversing said channel ways and having openings therethrough longitudinally spaced in accordance with a predetermined arrangement for successive registration with adjoining terminals of said channel ways, spring means for urging said valve in one direction, a rotatable cam shaft, and a cam carried on said shaft for urging said valve in an opposite direction, said cam having dwell portions corresponding to each registration of said certain openings and its associated channel way, and means under the control of said valve for cyclically releasing said shaft.

14. In a telegraph printing mechanism, a plurality of type actuating pneumatics, a tape feed actuating pneumatic, a set of selector plates having transverse openings permutably arranged, certain of said openings for individual conditions of selective alignment and certain of said openings selectable under multiple conditions of alignment of said plates, means responsive to telegraph signals for transversely positioning said plates, and conduit means for connecting said individually selectable alignments with said tape actuating pneumatics and said multiple selectable alignment with said tape feed actuating pneumatic.

15. In a telegraph printing mechanism, a plurality of type actuating pneumatics, a tape feed actuating pneumatic, and a pneumatic selector apparatus comprising a set of plates having perforations permutably arranged for individual alignment in accordance with each of said type actuating pneumatics and for multiple disposition alignment in accordance with said tape feed actuating pneumatic.

16. The combination set forth in claim 15 including means for simultaneously actuating said tape feed pneumatic concurrently with the actuation of each of said type actuating pneumatics.

17. A tension roller assembly including a tape guide and a tension roller mounted integrally upon a supporting structure and pivoted thereon intermediate said guide and roller spring means for urging said roller into operative position from

which the assembly is retractable by manipulation of said guide.

18. A mechanism for converting telegraphic permutation signals into corresponding fluid surges including a housing affording a main channel for conducting a source of fluid supply, said channel terminating opposite a pair of branch channels for affording alternative courses thereat, a control lever pivoted to reciprocate transversely 0 of said branch channels at its juncture with said main channel having an opening transversely thereof of size to align either of said branch channels with said main channel and having adjacent solid portions for concurrently closing the 5 other of said branch channels, a shuttle valve having openings therein each associated with one of said branch channels and capable of being aligned with its corresponding branch channel alternatively, a rotatable control shaft parallel- 10 ing the course of said main and said branch channels having a stop element, a stop arm normally presented in the path of said stop element, a pneumatically actuated piston for releasing said stop arm having a chamber communicating with 15 one of said branch channels, a distributor valve slideable longitudinally and having an opening transversely thereof of extensive bore at one side to communicate with the other of said branch channels and of reduced bore at its other side 20 to communicate with each of a plurality of distributive channels, cams carried by said shaft for actuating said valves in timed relation with the angular rotation of said shaft, and an electromagnetic device responsive to telegraphic signals 25 for fluttering said control lever accordingly.

19. In a printing mechanism, a printing platen, a plurality of type elements having alternatively effective printing impressions, a mounting for said printing platen shiftable so as to present 0 said platen to align with said printing impressions alternatively, and pneumatic means for shifting said platen mounting comprising a shift lever having a pivot intermediate its length, a pair of pneumatic pistons disposed at opposite sides of 5 said lever pivot, and fluid channeling means for connecting to the chambers of said pair of pistons alternatively a source of fluid supply and for concurrently establishing communication between 10

the chamber of the other and disconnected one of said pair of pistons with an avenue of escape.

20. In an automatic printing mechanism, a plurality of type carrying members, pneumatic actuating means for said members, a rotatable 5 platen for supporting a continuous web of material and for backing it to receive printed impressions from said type carrying members, tensioning means for urging the frictional engagement of said web of material with said platen, 10 and a pneumatic device for rotating said platen step by step during each printing operation and for thereby advancing said web of material comprising a ratchet wheel associated integrally with said platen, a pawl, and a pneumatic piston for 15 engaging and actuating said pawl having a piston chamber communicating with a source of fluid supply common to all of said pneumatic actuating means.

21. The combination set forth in claim 20 in 20 which said pawl is spring urged in the ratchet actuating direction and said pneumatic piston is directed to return said pawl in the opposite direction.

22. A fluid distributing organ for cyclic permutative operation comprising a main member 25 affording longitudinal passageway, a shuttle having openings transversely thereof, said shuttle being slideable through said main member in a direction transverse to said passageways, and rotatable means for moving said shuttle to align its 30 openings with divers ones of said passageways selectively.

23. In a pneumatically powered control unit, a plurality of pneumatic actuators allocated to 35 the performance of individually actuatable operations, a special pneumatic actuator assigned to the performance of an auxiliary operation accompanying the operation of a number of said plurality of pneumatic actuators, a set of selector 40 plates having transverse openings permutably arrangeable to afford transversely individual selectable paths for said plurality of actuators, and additional openings for affording a selectable path under multiple conditions of alignment of 45 said plates to said special pneumatic actuator.

EDWARD E. KLEINSCHMIDT.
